(57) **CLAIM**

The ornamental design for a modular cabinet, substantially as shown and described herein.

DESCRIPTION

FIG. 1 is a left perspective view of one embodiment of the modular cabinet,

FIG. 2 is a rear perspective view of the embodiment of the modular cabinet shown in FIG. 1.

FIG. 3 is a side view of the embodiment of the modular cabinet shown in FIG. 1.

FIG. 4 is a front view of the embodiment of the modular cabinet shown in FIG. 1.

FIG. 5 is a rear view of the embodiment of the modular cabinet shown in FIG. 1.

FIG. 6 is a top view of the embodiment of the modular cabinet shown in FIG. 1.

FIG. 7 is a left perspective view of the second embodiment of the modular cabinet.

FIG. 8 is a left perspective view of the third embodiment of the modular cabinet.

FIG. 9 is a left perspective view of the fourth embodiment of the modular cabinet.

FIG. 10 is a left perspective view of the fifth embodiment of the modular cabinet.

FIG. 11 is a left perspective view of the sixth embodiment of the modular cabinet.

FIG. 12 is a left perspective view of the seventh embodiment of the modular cabinet.

FIG. 13 is a left perspective view of the eighth embodiment of the modular cabinet.

FIG. 14 is a left perspective view of the ninth embodiment of the modular cabinet; and,

FIG. 15 is a left perspective view of the tenth embodiment of the modular cabinet.

The broken lines shown in the drawings are for illustrative purposes only and form no part of the claimed design.

1 Claim, 7 Drawing Sheets
